2 SHEETS—SHEET 2.

UNITED STATES PATENT OFFICE.

CLAUD W. ADAMS, OF WORCESTER, MASSACHUSETTS.

COIN-CONTROLLED BOTTLE VENDING AND EJECTING MECHANISM.

Application filed February 25, 1920. Serial No. 361,305.

To all whom it may concern:

Be it known that I, CLAUD W. ADAMS, a citizen of the United States of America, residing at the city of Worcester, in the county of Worcester and State of Massachusetts, have invented new and useful Improvements in Coin-Controlled Bottle Vending and Ejecting Mechanism, of which the following is a specification.

10 This invention relates to coin controlled mechanism and more specifically to means for ejecting bottles against the deposit of certain coins from an air cooled receptacle.

One of the objects of my invention is 15 to provide a device that will be capable of releasing a bottle containing soft drink or the like, said bottles being releasable, one at a time, and it being necessary to insert a certain coin or coins in order to effect this 20 bottle release.

Another object of my invention is to provide a coin controlled apparatus with a refrigerator which will enable the contents of the bottles to be cooled and thus to be in 25 a condition to be used by the person ejecting the same from this apparatus.

Another object of my invention is to provide in a device as described simple, inexpensive and highly efficient means designed 30 to automatically release bottles upon the deposit in coin chutes of determinate coins.

A still further object of my invention is to provide in a device as described mechanism for releasing bottles controlled by coin 35 mechanism, suitable means being provided for filling the bottle holding device with fresh bottles.

In the drawings wherein similar reference characters designate similar parts throughout the several views,

Figure 1 is a front elevation of my invention,

Figure 2 is a side elevation thereof, partly broken away,

45 Figure 3 is another side elevation of my invention,

Figure 4 is a cross-section thru the coin-controlled mechanism holding apparatus,

50 Figure 5 is a cross-section of the plunger showing a recess formed therein,

Figure 6 is a top plan view of the apparatus with the top removed,

Figure 7 is a perspective view of the bottle holding device,

Figure 8 are views, one in side elevation and the other in end elevation of a bottle rammer,

Figure 9 is a fragmental vertical sectional elevation of the bottle holding device,

Figure 10 is a cross-section thru the apparatus, showing the coin controlled mechanism,

Figure 11 is another cross-section thru said apparatus,

Figure 12 is a fragmental vertical sectional elevation of said apparatus,

Figure 13 is a cross-sectional view of the bottle holder,

Figure 14 is a top plan view of the toggle device forming a bottle support,

Figure 15 is a fragmental vertical sectional elevation of my invention,

Figure 16 is another fragmental vertical sectional elevation of the apparatus, and

Figure 17 is a side elevation illustrative 75 of the apparatus in folded position and in a position to be filled with bottles.

In the drawings which are merely illustrative of my invention, 1 designates the lower part of the apparatus which is in the 80 nature of a refrigerator and is adapted to contain ice. This portion 1 flares upwardly as at 2 and is connected to the main vertical portion or housing 3, which is closed at its upper end as at 4. In 85 order to place ice or any other cooling agent into the refrigerator, a door 5 is provided which is adapted to close entrance into said refrigerator, said door being hinged as at 6. Formed upon the housing 3 are 90 the coin slots 8 and 9 receiving respectively a dime and a nickel, one at a single time. The downwardly inclined coin chute 10 extends into communication with the coin slot 8 while the downwardly inclining chute 95 11 communicates at its upper end with the coin slot 9, the chute 10 being for nickels, while the chute 11 is for dimes.

The plunger 30 slides in a bearing 35 secured to a wall of the housing 3, and carries 100 fixedly thereon a cap 36 adapted to compress a spring 380 coiled around the plunger 30 and bearing directly against the bearing 35. This plunger also projects beyond the side of the housing and carries the button or push handle 38. At the inner end of the plunger 30 there is located a toggle lever arrangement providing a false bottom for

the bottle holder 44. Reference being had to Figure 14 it will be seen that the toggle consists of the links 50 and 50^a pivoted one on the other at 52, the link 50 projecting 5 between the lugs 54 secured to the housing 3, while the other two toggle links 51 and 51^a are pivoted one onto the other as at 52, the inner ends of links 50, 51 being pivoted upon the pivot 53 located in the lugs 54. 10 The links 50^a and 51^a are further pivoted together as at 55 upon the plunger 30. This plunger 30 also carries an auxiliary bottle supporting element in the form of a fork 42 formed up on a stem 41 which is in turn 15 disposed at right angles to the vertical rod 40 which is secured in upstanding relation directly upon this plunger. It will thus be seen that the fork is virtually in a horizontal plane when ready for operation. 20 The bottle holder 44 is preferably made of flexible steel or sheet metal and may be round in cross-section as illustrated in Figure 4 or it may be of the form illustrated in Figure 6 where it will be seen that the sheet 25 metal bottle holder is slit as at 48 thus providing the oppositely-arranged horizontally extending offsets 47 secured upon the blocks 46, the latter being secured directly against one of the walls of the housing 3. With this 30 bottle holder properly positioned as shown in Figure 6 it will be readily seen that cool air may readily reach the interior of this sheet metal bottle holder thru the slit 48, the lower end of this bottle holder terminating 35 directly over the toggle arrangement shown in Figure 9, the latter forming a false bottom for the bottles held in said bottle holder 44. Instead of the form of bottle-holder shown thus far any other suitable make of 40 bottle holding means may be employed. The lower end of the holder 44 is formed with a slot 56 thus providing a spring finger 57 which is concavo-convex in cross-section, and it is to be noticed that the upper end of this 45 spring 57 is slightly below the slot 43 thru which is adapted to project the work 42, this slot being of course formed in the bottle holder 44. The spring 380 will normally hold the plunger 30 projected outwardly of 50 the housing 3, and will also hold the bottles that are ejected against dropping too freely down into the delivery chamber 7 formed thru the apparatus. The bottles are designated 55 and are arranged in vertical alignment, one resting directly on top of the one beneath, and each having its bottom resting upon the neck of the bottle beneath it, if there be one.

The casing or housing 3 is hingedly connected upon the portion 2 of the apparatus so that it may be swung down from a vertical to a substantially horizontal position. In this position after the cap 4 has been removed, fresh bottles may be introduced into 60 the bottle holder 44, and the rammer 61 hav-

ing the head 63 and flexible cushion 64 thereon may then be taken hold of by its handle 62, the rammer forcing each bottle into position, one next to the other within the bottle holder 44. In Figure 4, 49 designates a conduit which is formed separately from the bottle holder 44, and may extend down as far as the refrigerator so as to receive the cold air. 70

I will now describe the operation of my invention. 75

It will be seen that when the plunger is released from locked position it may then be pushed along in the guide 35, and as the forward end of this plunger moves ahead it 80 will operate the toggle arrangement, the spring 380 being compressed as the plunger is pushed forwardly, and this spring when uncompressed has been designed to hold the toggle in full closed position under the bottle holder as shown in Figure 11. When the toggle is closed the sets of levers will provide too small an opening to permit bottles to descend therethru, but when the plunger is moved forwardly the toggle will be moved 85 to full open position as shown in Figure 14 as well as 10, and the opening thus provided by this toggle will be sufficiently large to admit bottles therethru. Normally, i. e. when the plunger projects its full distance outside 90 of the housing 3, the auxiliary bottle supporting element including the fork 42 will be disposed in advance of the slot 43 of the holder 44. When, however, the plunger is moved forwardly and the toggle is in full 100 open position the fork has been moved its full distance within the holder as shown in Figure 10. As soon as the toggle begins to open however, the fork begins to enter the slot 43 formed in the housing 44, and begins 105 to support the bottles directly above the one resting upon the toggle which bottle gently falls against the opposition of the spring 57 which will check its too free descent. By the time the bottle 55 has been ejected upon the 110 seat 58 resting upon the springs 59 the fork will support the other bottles. In this manner only one bottle may be ejected at a single time.

As soon as the operator releases pressure 115 from the plunger, the spring 380 will expand pulling back the element 42 out of the slot of the holder 44, and restoring the parts to normal locking position.

I do not make any claim herein to the 120 coin-controlled mechanism in itself, as it constitutes the subject matter of my divisional application, Serial No. 426,069 filed Nov. 23, 1920. I am aware of the fact that modifications can be made in the construction illustrated without departing from the scope of the invention as expressed in the claims. Therefore I do not wish to be limited to all the details of construction herein 125 shown and described, but 130

What I desire to claim and secure by Letters Patent is;

1. In a device as described, in combination, a bottle holding receptacle, means for supporting bottles right side up on end in vertical alinement, means in said receptacle for retarding the feeding of said bottles, manually controlled means for displacing said support, and check controlled mechanism for controlling the operation of said support. 5
2. In a device as described, in combination, a vertically extending receptacle having a gravity bottle feed, an expandable and contractible false bottom therefor, a pusher mechanism for actuating said false bottom, said false bottom when expanded having an open center adapted to admit a bottle there thru, a locking member normally engaging said pusher mechanism to cause said false bottom to be contracted and means controlled by the deposit of coins upon said locking member for releasing the latter. 10
3. In a device as described, in combination, bottle magazine, having a quickly releasable bottom supporting bottles, and movable to release bottles, an auxiliary bottle support moving in unison with said movable bottom, said movable bottom and said false bottom moving in the same direction, the first to release and the second to support the bottles and means to retard the delivery of bottles. 15
4. In a device as described, in combination, a bottle holding receptacle, manually controlled means for opening said receptacle for releasing a bottle, a coin controlled lock for said means and means engaging the neck of a bottle to prevent the discharge of all the bottles from the receptacle. 20
5. In combination, a tube holding bottles, coin controlled mechanism movable under said tube to support bottles therein, bottle holding means carried by said mechanism and comprising bottle neck-engaging means, and a manually controlled actuator for said mechanism. 25
6. In a vending device, the combination of a bottle magazine, two expandable bottle supporting means movable in opposite direc- 30
7. In a vending device, the combination of a bottle magazine, oppositely and outwardly expandable bottle supporting means in combination with slidable bottle supporting means and check-controlled means controlling the operation of both of said supporting means. 35
8. In a vending device, the combination of a bottle magazine, bottle releasing means adapted to grip a bottle, delivery retarding means, and check-controlled means, controlling the operation of said releasing means. 40
9. In a vending device, the combination of a bottle magazine having a gravity bottle feed, an expandable and contractable false bottom therefor associated with a bottle neck supporting member, and a pusher mechanism for actuating said false bottom and neck supporting member. 45
10. In a vending machine, the combination with a vertical chute for supporting articles one above another, of a lazy tongs support for the articles at the bottom of said chute and means for spreading said lazy tongs to allow the bottom article to drop down between them. 50
11. In a device as described, in combination, bottle supporting mechanism having a member providing an outlet for bottles, manually controlled mechanism for moving said member in and out of position, a locking detent for said mechanism, and means controlled by the presence of two coins of varying sizes for releasing said detent. 55
12. In a device as described, in combination, a vertically extending receptacle including a refrigerator, slidable means for supporting bottles, a bottle ejector carried by said means and mechanism controlled by a plurality of coins for timing the operation of said bottle ejector. 60

In witness whereof I have hereunto set my hand this second day of February, 1920.

CLAUD W. ADAMS. [L.S.]
